THREAD BOBBIN AND METHOD OF PRODUCING THE SAME

Rowland N. Robinson, Dedham, Mass.

Application November 13, 1936, Serial No. 110,687

6 Claims. (Cl. 112—251)

This invention relates to thread bobbins and to a method of producing the same.

An object of this invention is to devise a thread bobbin in which the head is securely and non-rotatably fixed to the core in a simple manner.

Another object is to devise a means and method whereby the heads may be automatically and accurately centered around the core ends during the pressing operation.

A further object is to produce such a means and method which will secure the head to the core non-rotatably as specified above.

A still further object is to secure the heads to the core so that the heads will not collapse in operation even when all of the thread mass has been unwound.

The foregoing and other objects of my invention will be best understood from the following description of exemplifications thereof, reference being had to the accompanying drawings, wherein:

Fig. 1 is a cross-sectional view of a bobbin with the heads in position to be forced over the core ends;

Fig. 2 is a cross-sectional view showing the heads forced over the core ends but not secured in place;

Fig. 3 is a cross-sectional view of the completed bobbin after it has been pressed to shape and the heads fastened in position;

Fig. 4 is a diagrammatic showing of a mechanism for producing the steps shown in Figs. 1, 2, and 3;

Figs. 5 and 6 are views showing the mechanism of Fig. 4 in different stages of producing a bobbin; and

Figs. 7, 8, 9 and 10 show different types of head blanks which may be used.

In order to produce my novel bobbin, a mass of thread is cross-wound upon a tubular core 2 of paper or similar compressible material usually used in bobbins. The core 2 is made longer than the depth of the thread mass 1 so that the ends 45 of the core extend a substantial distance beyond the thread mass as shown. Heads 3 of some suitable material, such as paper, cellulose products, and the like, are placed opposite the ends of the core 2, as shown in Fig. 1. The heads 50 3 are each provided with a central opening 4. This opening is preferably made with a diameter of the same size as the inner diameter of the core 2 for a reason to be discussed below.

The heads 3 are then forced down over the 55 ends of the core 2 to the position shown in Fig. 2.

Since the outer diameter of the core 2 is greater than the diameter of the openings 4, the inner edges of these openings will be turned outward as shown at 5 in Fig. 2. The heads at this time will have a firm grip on the core 2. However, in order to secure these heads in place to the degree which I desire, the outer ends of the core 2 are turned down over the edges 5 to produce the interlocking connection 6 between the edges of the core 2 and the edges of the opening 4, as shown in Fig. 3. During this last step the bobbin may be pressed to shape and size. In pressing the ends of the core 2 to form the interlocking connection 6, the central parts of the bobbin are indented to form the depressions 7 so that in the completed bobbin the outer ends of the core 2 lie in the same plane as the flat portions of the heads 3.

The bobbin construction described above lends itself admirably to construction by automatic machinery of a very simple type, particularly since the mounting of the heads and the pressing operation may be accomplished at the same time in a single machine. The mechanism diagrammatically shown in Fig. 4 may readily be incorporated in such automatic machinery. This mechanism consists of an elongated punch 8 having a tapered nose 9. The punch 8 moves inside of a press punch 10 arranged concentrically with said punch 8. A space is left between the punch 8 and the press punch 10 in which space is placed a crimping tool 11. Thus the crimping tool 11 is also concentric with the punch 8 and the punch press 10. Facing the punch 8, punch press 10 and crimping tool 11 is a similar press assembly consisting of a press punch 12 and a crimping tool 13 substantially identical with the press punch 10 and crimping tool 11, respectively. The crimping tool 13 is provided with a bore 14 into which the punch 8 projects during a portion of the operation. Of course it is to be understood that each of the members 8, 10, 11, 12, and 13 are each actuated by suitable operating mechanism to produce the motions to be described below.

A core 2 and thread mass 1 are fed into position between the two press assemblies. A head 3 is fed into position adjacent the face of the press punch 10, and another head 3 is fed into position adjacent the face of the press punch 12. The punch 8 is then moved to the left in the direction of the arrow in Fig. 4, and by the action of the tapered nose 9 threads itself through the opening in the center of the right-hand head 3. The punch 8 is made substantially of the same diameter as the in-

ner diameter of the core 2. Since the opening 4 in the head 3 is also of this diameter, as indicated above, the head 3 automatically centers itself on the punch 8. As the punch 8 moves further to the left, it enters the core 2 and likewise centers said core on said punch. As the motion of the punch continues, it likewise threads itself through the opening in the left-hand head 3, and likewise centers said head upon said punch. This centering of the heads 3 and core 2 is important since if such centering did not occur, a defective bobbin would be produced.

After the heads 3 and core 2 have been threaded upon the punch 8, the punch continues its travel until it has entered the bore 14 of the crimping tool 13, as shown in dotted lines in Fig. 4. Thereupon the punch 8 serves as a guiding member for the members 10, 11, 12, and 13 so as to insure an accurate impingement of these members on the bobbin. The bobbin at this time is substantially in the condition as shown in Fig. 1.

The press punches 10 and 12 are then actuated to approach the bobbin. This motion pushes the heads 3 along the punch 8, and forces said heads over the ends of the core 2 until said heads reach the thread mass, at which time the press punches 10 and 12 firmly engage the sides of the thread mass. At this time the bobbin is substantially in the condition as shown in Fig. 2, and the mechanism is substantially in the position as shown in Fig. 5.

During the above travel of the press punches 10 and 12, the crimping tools 11 and 13 travel with said press punches lagging behind them to the degree substantially as shown in Figs. 4 and 5. The punch presses are then further actuated to compress the thread mass to its final shape. During the pressing operation the crimping tools 11 and 13 are brought forward so that at the end of the pressing operation they are substantially flush with the outer end of the press punches 10 and 12, respectively, as shown in Fig. 6. The crimping tools, therefore, turn over the ends of the core 2 to produce the interlocking connections 6 and also the depressions 7. At the end of this pressing step, the bobbin is completed substantially in the form as shown in Fig. 3. The punch 8 is withdrawn first and then the members 10, 11, 12, and 13 are withdrawn, whereupon the completed bobbin drops out of the mechanism. The operation may then be carried out again upon the next bobbin.

The heads 3, which may be used, are usually circular in shape but the opening 4 may assume any convenient form as long as the principles described above are satisfied. For example, the opening 4 may be circular as shown in Fig. 7. The opening may be provided with a number of slits 15, as shown in Fig. 8, to facilitate the turning back of the edges to the position shown in Fig. 2. This enables stiffer material to be used in some cases. A still further form is shown in Fig. 9 where the opening 4 is provided with a series of projections 16. The diameter formed by the inner ends 17 of the projections 16 is preferably the same as the inner diameter of the core 2. The projections need not be pointed as shown, but may be of any other shape, such as, for example, are shown in Fig. 10 where projections 18 of oblong shape are provided. If it is desired to supply a greater amount of material from the head 3 to form the interlocking connection 6, the diameter of the hole 4 may be made somewhat smaller than the inner diameter of the core 2. In each case where the diameter of the hole 4 is specified,

this is to be taken as meaning the diameter of the opening formed by the inner ends of such projections as 17 or 18 if such projections are present.

Bobbins constructed as described above have the heads 3 very securely fixed in place. One drawback of previous constructions has been that as the thread mass is unwound, the heads have a tendency to move inwardly and collapse when the last few turns remain upon the core. The novel bobbins described herein retain the heads so firmly in place that all of the thread may be unwound without the heads 3 collapsing.

This invention is not limited to the particular details of construction, materials, or processes as described above, as many equivalents will suggest themselves to those skilled in the art. It is accordingly desired that the appended claims be given a broad interpretation commensurate with the scope of the invention within the art.

What is claimed is:

1. A thread bobbin comprising a tubular core, a thread mass wound on said core, and a head mounted on each end of said core overlying the ends of said thread mass, each head having a central opening surrounding an end of said core, the edge of said opening and the wall of said core at said end being bent into transversely arcuate interlocking relation.

2. A thread bobbin comprising a tubular core, a thread mass wound on said core, and a head mounted on each end of said core overlying the ends of said thread mass, each head having a central opening surrounding an end of said core, the diameter of said opening being equal to or less than the inner diameter of said core, each head being located over an end of said core, the edge of said opening and the wall of said core at said end being bent into transversely arcuate interlocking relation.

3. The method of making a thread bobbin comprising the steps of winding a thread mass upon a tubular core so as to leave the ends of said core projecting beyond said thread mass, forcing a head having a central opening with a diameter equal to or less than the inner diameter of said core over each end of said core, turning the edges of said opening outwardly to lie closely along the outer walls of said core, pressing said thread mass to shape and pressing upon the outer ends of said core to turn back said outer core ends and said outwardly-turned head edges to form an interlocking connection with each other.

4. The method of making a thread bobbin comprising the steps of winding a thread mass upon a tubular core so as to leave the ends of said core projecting beyond said thread mass, threading a head having a central opening with a diameter equal to or less than the inner diameter of said core upon an elongated punch having a diameter substantially equal to the inner diameter of said core, threading said core upon said punch, threading another head similar to said first head upon said punch, forcing said heads along said punch over the core ends into intimate contact with the ends of said thread mass, turning the edges of said opening outwardly to lie closely along the outer walls of said core, pressing said thread mass to shape and pressing upon the outer ends of said core to turn back said outer core ends and said outwardly-turned head edges into interlocking connection with each other.

5. A thread bobbin comprising a tubular core, a thread mass wound on said core, and a head mounted on each end of said core overlying the

5 ends of said thread mass, each head having a round central opening surrounding an end of said core, the diameter of said opening being smaller than the outside diameter of said core, each head being located over an end of said core, the edges of said opening and the walls of said core at said end being bent into transversely arcuate interlocking relation.

10 6. A thread bobbin comprising a tubular core, a thread mass wound on said core, and a head

5 mounted on each end of said core overlying the ends of said thread mass, each head having a central opening with a serrated edge surrounding an end of said core, the diameter of said opening being smaller than the outside diameter of said core, each head being located over an end of said core, the edges of said opening and the walls of said core at said end being bent into transversely arcuate interlocking relation.
